STEAM IRON

Philip J. More, Evanston, and John B. McCord, Chicago, Ill., assignors to Birtman Electric Company, a corporation of Illinois

Application January 15, 1954, Serial No. 404,276

4 Claims. (Cl. 38—77)

This invention relates to a steam iron including a water reservoir, a steam generator, a valve between the reservoir and generator and a handle, including a hollow front post. The invention particularly pertains to apparatus for filling the reservoir in such an iron with water.

One of the principal types of steam irons is known as the flash type in which water is contained within a reservoir and then is released through a controllable valve into a steam generator which is ordinarily located in the soleplate of the iron adjacent to the toe thereof where it can receive a maximum amount of heat from the electric heating element located in the soleplate.

One of the principal problems in such a steam iron is the provision of means for filling the reservoir with water. It is necessary that water be permitted to flow into the reservoir at a sufficiently rapid rate and it is also necessary that the reservoir be vented to relieve internal pressure and that means be provided to prevent the water splashing out the reservoir while the iron is in use.

The inventions described and claimed herein successfully solve these and other problems by providing an improved fill tube construction. The invention will be described as related to the embodiment shown in the accompanying drawings. Of the drawings:

Figure 1 is a side elevational view, partly in section, of a steam iron embodying the invention;

Figure 2 is a sectional view taken substantially along line 2—2 of Figure 1;

Figure 3 is a front elevational view of the iron;

Figure 4 is a side elevational view of the fill tube member prior to its assembly with the remainder of the iron;

Figure 5 is a plan view of the tube of Figure 4.

The steam iron shown in the accompanying drawings comprises a soleplate 10 having a tubular heating element 11 embedded therein and containing a steam generator including a steam generating chamber 12 located within the soleplate. The steam generating portion and steam distributing portion of the iron are of the usual type wherein water is converted to steam in one portion of the soleplate and ejected through passages in the bottom surface of the soleplate onto the material being ironed. Such steam generator and conduit systems are common to steam irons of this type and are well known to those skilled in the art.

Positioned on the top of the soleplate 10 is a closure plate 13 which operates as a closure for the steam generating chamber 12. Located above this plate 13 is a water reservoir 14 that is enclosed within a sheet metal hood 15. On top of this hood is positioned a handle 16 provided with a hollow front post 16a and a rear post 16b. The bottom portion 16c of the handle contains a control knob 17 for regulating the temperature of the iron. This bottom portion is connected by a plurality of screws 18 to the top of the hood 15.

Attached to the front upper portion of the reservoir

2

14 and extending upwardly generally into the hollow front post 16a is an apparatus including a fill tube 19. This fill tube is provided with a bottom flange 19a rolled over as shown in Figure 1 to grasp tightly the marginal edge of an opening in the upper front portion of the reservoir. The fill tube is provided with a front wall 19b and a rear wall 19c spaced from each other to define a filling passage 19d. Both the front and rear walls are curved so that the filling passage 19d is arcuately curved as shown in Figures 2 and 5.

The front wall 19b of the tube is considerably shorter than the rear wall 19c so as to provide a filling opening 19e. This filling opening is essentially rectangular and curved. Its bottom edge is defined by the top edge of the front wall 19b and its side edges are essentially parallel to each other. The top edge of this filling opening is defined by the bottom surface of a forwardly-projecting ledge 19f, with this bottom surface being sloped inwardly and downwardly as shown in Figure 1. As can be seen in Figure 5, the opening 19e is of less width than the filling passage 19d so that the sides of the passage extend beyond the corresponding sides of the opening 19e.

In order to control the flow of water between the reservoir 14 and the steam chamber 12 there is provided a valve 20. This valve has an internal passage 20a and a conical valve seat 20b. This conical valve seat is at the bottom of a relatively large passage 20c which communicates with side passages 20d so that water from the reservoir is led through these passages 20d into the passage 20c and thus past the valve seat into the relatively small passage 20a from which the water flows into the chamber 12. The valve 20 is mounted on an inverted, essentially dish-shaped sheet metal stamping 21. This stamping is mounted on the closure plate 13 so as to extend across an opening 13a therein. The valve 20, which is mounted on the stamping 21 and on the bottom surface of the reservoir 14 has its bottom extending through this opening 13a. The edge of the stamping 21, which is essentially planar, is held on the plate 13a by a rolled edge part 13b.

The operating stem for the valve is in the form of a rotatable rod 22 having a conical lower end adapted to seat on the conical valve seat 20b. The rod 22 extends upwardly into the hollow front post 16a of the handle and is located rearwardly of the rear wall 19c of the fill tube 19.

In order to hold the rod 22 for rotation in controlling the flow of water through the valve into the steam chamber, the upper end of the fill tube 19 is provided with a generally rearwardly-extending bracket 23. This bracket is mounted on the upper end of the fill tube and is provided with an internally threaded opening 23a rotatably supporting a threaded member 24 to which the rotatable rod 22 is secured. The upper end 22a of this rod 22 beyond the threaded member 24 is serrated longitudinally and slidably engages a similarly serrated opening 25a extending through a rotatable disc 25 housed within a slot 16d in the upper front part of the handle 16. The disc 25 extends beyond the slot on the front and sides so as to be readily grasped by the hand for rotation of the disc. Rotation of the disc 25 rotates the rod 22 and threaded member 24 and causes this assembly to be moved upwardly or downwardly to control the flow of water through the valve 20.

Positioned on the bottom of the fill tube 19 and extending rearwardly thereof is a second bracket 26. The rod 22, likewise, extends through an opening 26a in this bracket. Extending across this opening adjacent to the top thereof is a gasket 27 preferably made of neoprene or similar synthetic rubber, having the edges clamped between annular rings 28 held within a recess in the

second bracket 26 as shown most clearly in Figure 1. The gasket 27 which makes a sliding contact with the rod 22 serves to bar the entrance of water from the reservoir 14 into the hollow front post 16a of the handle 16.

Located within the reservoir 14 rearwardly of the valve 20 and rod 22 is a transverse baffle 29. This baffle may be fastened in place by any means desired such as rivets 30 and is provided with elongated slots 29a remaining after portions 29b are struck from the baffle 29. This baffle 29 is intended to prevent extreme surges of water in the reservoir while the iron is being used. As can be seen from the above description of the invention and as is shown in the drawings, the fill tube and associated structure of this invention provides an apparatus that permits rapid and easy filling of the reservoir when the iron is upended on its heel 31. Furthermore, although the filling passage 19d is relatively thin, as shown in Figure 1, the passage is sufficiently wide so that a large volume of water can be poured into the reservoir. Furthermore, the passage is preferably curved so that water poured through the upended opening 19e will strike the curved rear wall 19c and flow against the sides of the passage 19d into the reservoir 14. This construction not only provides rapid flow of water, but also aids in preventing outward splashing of water while it is being poured.

Another very important advantage of the construction described and claimed herein is that the water-filled passage is kept separate from the portion of the iron housing the upper part of the valve operating mechanism. As is pointed out above, the gasket 27 prevents water entering the upper portion of the front post. Furthermore, in the preferred construction the apparatus, including the fill tube 19 and brackets 23 and 26, is made of integral one-piece construction. Thus, these parts may be made as a one-piece aluminum die casting. This one-piece construction not only reduces the cost of the iron but also permits installing this piece as a unit.

As was pointed out previously, the bottom surface of the forwardly-projecting ledge 19f being inwardly and downwardly sloped, aids in directing water into the passage 19d. Furthermore, the upper surface of this ledge serves to locate the front portion of the handle 16 relative to the fill tube 19. As is shown in Figure 2, the front portion of the fill tube blends smoothly with the adjacent sides of the front handle post 16a. This is accomplished by having the sides 19e of the fill tube arranged essentially radially so as to abut the adjacent side portions of the handle. This serves to present a pleasing appearance and also strengthens the assembly of fill tube and front handle post. The rear wall 19c of the fill tube extends a considerable distance rearwardly of the sides 19g as is shown in Figures 1 and 2.

Having described my invention as related to the embodiment shown in the accompanying drawings, it is my intention that the invention be not limited by any of the details of description, unless otherwise specified, but rather be construed broadly within its spirit and scope as set out in the accompanying claims.

We claim:

1. In a steam iron including a water reservoir, a steam generator, a valve between the reservoir and generator

and a handle including a hollow front post, apparatus comprising: a fill tube extending upwardly of the reservoir into the hollow post and having an opening for filling the reservoir with water, said fill tube having an area adjacent to the opening of crescent-shaped hollow cross-section with the ends of the crescent located on opposite sides of and rearwardly of said opening; and valve operating means within said hollow post substantially entirely exteriorly of the fill tube.

- 5 2. In a steam iron including a water reservoir, a steam generator, a valve between the reservoir and generator and a handle including a hollow front post, apparatus comprising: a fill tube extending upwardly of the reservoir into the hollow post, the tube being located in the 15 forward portion of the post and having a front opening for filling the reservoir with water; valve operating means including a rotatable rod within the hollow post rearwardly of the fill tube; a bracket on the upper end of the fill tube rotatably supporting said valve operating means; 20 a second bracket on the fill tube beneath the first bracket through which said rotatable rod extends; and a gasket held by said second bracket and contacting said rod, said fill tube in the area adjacent to said opening having a crescent-shaped hollow cross-section with the ends of the 25 crescent located on opposite sides of and rearwardly of said opening.

3. In a steam iron including a water reservoir, a steam generator, a valve between the reservoir and generator and a handle including a hollow front post, apparatus 30 comprising: a fill tube extending upwardly of the reservoir and having an opening for filling the reservoir with water, said fill tube having an area adjacent to the opening of crescent-shaped hollow cross-section with the ends of the crescent located on opposite sides of and rearwardly of said opening; and valve operating means for 35 opening and closing said valve.

4. In a steam iron including a water reservoir, a steam generator, a valve between the reservoir and generator and a handle including a hollow front post, apparatus 40 comprising: a fill tube mounted on the top of the reservoir extending upwardly of the reservoir into the forward portion of the hollow post and having a forwardly directed opening for filling the reservoir with water; a bracket mounted on the fill tube extending rearwardly thereof 45 located in the rear portion of the hollow post; and valve operating means supported on said bracket positioned within the rear portion of said hollow post substantially entirely exteriorly of the fill tube, said fill tube in the area adjacent to said opening having a crescent-shaped hollow cross-section with the ends of the crescent located on opposite sides of and rearwardly of said opening.
